(57) CLAIM

The ornamental design for a display screen with graphical user interface, as shown and described.

DESCRIPTION

FIG. 1 is a front view of a display screen with graphical user interface showing our new design;

FIG. 2 is an alternative embodiment of a display screen with graphical user interface showing our new design;

FIG. 3 is an alternative embodiment of a display screen with graphical user interface showing our new design;

FIG. 4 is an alternative embodiment of a display screen with graphical user interface showing our new design;

FIG. 5 is an alternative embodiment of a display screen with graphical user interface showing our new design;

FIG. 6 is an alternative embodiment of a display screen with graphical user interface showing our new design;

FIG. 7 is an alternative embodiment of a display screen with graphical user interface showing our new design;

FIG. 8 is an alternative embodiment of a display screen with graphical user interface showing our new design;

FIG. 9 is an alternative embodiment of a display screen with graphical user interface showing our new design;

FIG. 10 is an alternative embodiment of a display screen with graphical user interface showing our new design;

FIG. 11 is an alternative embodiment of a display screen with graphical user interface showing our new design;

FIG. 12 is an alternative embodiment of a display screen with graphical user interface showing our new design; and,

FIGS. 13-24 are enlarged views of the solid line subject matter shown in FIGS. 1-12, shown separately for completeness of illustration.

The outermost broken line and the broken line showing of the circular feature illustrate an electronic device. The remaining broken lines illustrate portions of the graphical user interface and portions of the display screen. None of the broken lines form part of the claimed design.
